(57) **CLAIM**

The ornamental design for a handle for a knife as shown and described.

DESCRIPTION

FIG. 1 is a front elevational view of a handle for a knife showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a right, front, bottom perspective view thereof; and, FIG. 8 is a left, rear, top perspective view thereof.

In the drawings, the broken lines are shown for the purpose of illustrating both parts of the article as well as boundaries of the claim. None of the broken lines form part of the claimed design.
